METHOD OF MAKING A MULTIPLE PART ANCHORAGE

Louis H. Morin, Bronx, N. Y.

Application September 22, 1952, Serial No. 310,903

2 Claims. (Cl. 29—417)

This invention relates to a method of making what may be termed multiple part anchorage members such, for example, as members which are internally threaded for reception of a screw or, in other words, such members as expansion shields and anchor members for mountings on sheet materials of various kinds and classes. Still more particularly, the invention deals with a method of forming members of the character described, wherein the separate parts of the resulting member are simultaneously formed and united on a wire or strand and then folded thereon to bring the parts into close proximity to each other to form a member of substantially round cross-sectional contour having spaced threaded sections extending longitudinally of at least part of the bore of said member.

The novel features of the invention will be best understood from the following description, when taken together with the accompanying drawing, in which certain embodiments of the invention are disclosed and, in which, the separate parts are designated by suitable reference characters in each of the views and in which:

Fig. 1 is a diagrammatic face view of one part of a die illustrating the formation of the several parts of an expansion shield on a joining strand or wire.

Fig. 2 is a section substantially on the line 2—2 of Fig. 1 breaking through the uniting wire or strand and omitting parts of the construction and also showing, in section, forming tools for shaping the members into final assemblage form.

Fig. 3 is a broken off side elevation of a shield made according to my invention, looking in the direction of the arrow 3 of Fig. 4.

Fig. 4 is an end view of the structure as shown in Fig. 3, parts of the construction being omitted.

Fig. 5 is an end view of a modified form of product arranged on a coupling strand, the parts assuming a position similar to the shields shown in Fig. 2, but omitting the dies.

Fig. 6 is a side view of the product of Fig. 5.

Fig. 7 is an end view of an anchor member made from the structure shown in Figs. 5 and 6; and

Fig. 8 is a section on the broken line 8—8 of Fig. 7, omitting the background showing and also indicating in section a mounting in which the member is adapted to be arranged.

In Figs. 1 and 2 of the drawing, I have shown at 10 a die or part of a die having vertically spaced cavities 11, 12 and 13, the cavity 11 being located intermediate the cavities 12 and 13 and these cavities are shaped to form respective parts 14, 15 and 16 of a resulting multiple part anchorage member, such for example, as an expansion shield generally shown in assembled relationship at 17 in Figs. 3 and 4 of the drawing. The separate parts 14, 15 and 16 will be shaped so as to produce, when the parts are assembled, proper alignment of the internal threads 18 in the bore 19 of the shield, as well as proper alignment of the external ribs 20 extending longitudinally of one end portion of the shield. The other end portion

2

of the shield terminates in what may be termed a cylindrical body 21 having spaced longitudinally extending grooves or recesses 22 between adjacent parts 14, 15 and 16 in which a strand or wire 23 is arranged in the manner clearly illustrated in Fig. 4 of the drawing.

In forming the parts 14, 15 and 16 in the dies, said parts are cast directly upon the strand or wire 23, the latter being a flat wire or strand in the construction shown.

At 24 I have shown a gate or sprue passage in the dies for extending the cast metal or other injected moulded material into the respective cavities 11, 12 and 13 and at 25 I have shown carrying lugs in the form of open ring-like members, which lugs are formed upon a carrying pin 26 disposed between the dies, said pin being utilized to support the cast parts 14, 15 and 16 when the dies are separated and in moving said parts downwardly into a position beyond the lower surface 27 of the dies, after which, the dies are partially closed and the pin 26 is stripped from the lugs by upward movement.

When the parts are in the lowered position, they may be simply trimmed in conventional manner to remove the gate or sprue 24 and the lugs 25 and the strand 23 sheared at the lower surface 27 of the die. It is preferred, however, that these parts be positioned between two forming tools 28 and 29, the tool 28 being preferably stationary and the tool 29 moved toward and from the tool 28 to fold or form the parts 14, 15 and 16 around a mandrel 30. The mandrel 30 has a large diameter portion 31 which fits in the bore 32 of the cylindrical body 21, whereas the small diameter 33 of the mandrel will fit within the threads 18 of the bore 19, so that, when the forming tools 28 and 29 are separated, the resulting expansion shield can drop freely from or be displaced from the mandrel as a finished trimmed product.

It will be apparent that the tools 28 and 29 will be of a dimension within the overall length of the shield parts 14, 15 and 16 so as to facilitate trimming of the gate 24 and lugs 25. The tool 29 can also include a shearing plate 29' for shearing the strand 23 in the operation of the tool 29.

It will be apparent that the strand 23 will be of such characteristics as to hold the parts 14, 15 and 16 in the assembled relationship shown in Figs. 3 and 4 with adjacent surfaces of the parts substantially abutting. In this way, the use of the conventional split rings and other fasteners for holding parts of this type and kind together can be dispensed with.

It will appear from a consideration of Figs. 1 and 3 of the drawing that the bore 19 is tapered, whereas the bore 32 is straight and that the outer surface, on which the ribs 20 are formed, is normally substantially straight so as to provide the usual expansion properties of the shield in the use thereof as with other devices of this type and kind.

In Figs. 5 to 8, inclusive, I have shown a modified adaptation of my invention, wherein a series of parts 34, 35 and 36 are formed upon a wire or strand 37 in the same manner of formation of the parts 14, 15 and 16 on the strand 23. However, in the latter figures, an anchorage device 38 is formed in the resulting assemblage of the parts by bringing these parts into abutting engagement with each other and bending the strand 37 in the manner clearly illustrated in Fig. 7 of the drawing. Here again, the parts have internal threads as at 39, which extend the major portion of the length of the resulting bore formed between these parts, one end of the parts having a reduced unthreaded bore 40. The strand or wire 37, in the construction shown, is of round cross-sectional form and the outer surface of the respective

parts 34, 35 and 36 have threads as at 41 and, in bringing the parts together in the assemblage or annular relationship shown in Fig. 7, the threads 39, as well as the threads 41, are brought into proper alignment with each other, it being understood that, in forming the parts, the threads will be fashioned to accomplish this result. 5

Associated with the anchor member 38 shown in Fig. 8 of the drawing is part of a sheet or panel 42, having a threaded socket 43 adapted to receive the member 38. It is preferred that one of the threads 39, 41 be opposed to that of the other, for example, the thread 39 can be a right hand thread; whereas, the thread 41 can be a left hand thread and, in this event, the threads of the socket 43 will be correspondingly formed. Anchorage devices, such as shown in Figs. 5 to 8, inclusive, can be utilized in support of articles of various types and kinds, on wall or panel structures of any type or kind and, in some instances, the several parts of the member 38 can be expanded into a socket of a support, such as the support 42 to establish anchorage in a socket, like the socket 43. This is possible with materials of certain types and kinds, where the material is sufficiently yieldable to accomplish this result. 20

One of the distinct advantages in my improved construction resides in the fact that the several parts of the anchorage member are definitely aligned on and by the strand and, by virtue of the direct assemblage on the strand, materially simplifies the cost of producing devices of the kind under consideration. The labor saving is readily apparent from the standpoint of dispensing with handling and with the cost of assembling a split or other ring on the several parts of the member in holding the same together. 25

From a standpoint of description, the anchorage member may be said to comprise circumferentially arranged arc-shaped sections defined by the parts spaced along the strand with the strand bent intermediate the sections or parts, except where the ends of the strand terminate in one of the recesses between adjacent sections. These sections may also be said to have internal and external irregular or threaded portions. The sections or cast parts may be said to be formed on an insert, the wire or strand comprising such insert and that the insert is formed to create the assemblage of the parts or sections. 30 As may be appreciated, anchorage members having more than three sections may be produced by the method described. 45

Having fully described my invention, what I claim as new and desire to secure by Letters Patent is:

1. Method of continuously and successively forming 50 multiple part anchor members on a continuous length of strand comprising moving a short length of said strand between a pair of relatively movable dies and adjacent a movable transfer core disposable between the dies, said dies having mating cavities for forming said parts, said short length being straight and having a free end disposed between said dies while the other end thereof extends beyond the dies and is integrally joined to said 55

continuous length, closing the dies and casting a plurality of threaded parts in spaced side by side relation about said short length of strand by injecting casting material in one injection step to said dies, said short length becoming embedded in said parts, simultaneously forming on each part during said injection a lug portion in engagement with said transfer core, opening the dies, moving said parts and embedded length out of the dies by moving said transfer core and at the same time moving a succeeding short length of strand between the dies, partially closing the dies about the transfer core and stripping the latter from said lug portions, trimming said parts, severing the embedded length from said succeeding short length, moving said parts into a circumferential relation with respect to one another by bending the embedded length or portions thereof intermediate said parts, thereby forming an anchor member, and casting a succeeding plurality of threaded parts about said succeeding short length of strand during said trimming, severing, and bending steps.

2. Method of continuously and successively forming multiple part anchor members on a continuous length of strand comprising moving a short length of said strand between a pair of relatively movable dies and adjacent a movable transfer core disposable between the dies, said dies having mating cavities for forming said parts, said short length being straight and having one end integrally joined to said continuous length, closing the dies and casting a plurality of threaded parts in spaced side by side relation about said short length of strand by injecting casting material in one injection step to said dies, said short length becoming embedded in said parts, simultaneously forming on each part during said injection a lug portion in engagement with said transfer core, opening the dies, moving said parts and embedded length out of the dies by moving said transfer core and at the same time moving a succeeding short length of strand between the dies, partially closing the dies about the transfer core and stripping the latter from said lug portions, trimming said parts, severing the embedded length from said succeeding short length, moving said parts into a circumferential relation with respect to one another by bending the embedded length at portions thereof intermediate said parts, thereby forming an anchor member, and casting a succeeding plurality of threaded parts about said succeeding short length of strand during said trimming, severing, and bending steps.
